Primary Examiner — Brandon Michael Rosati*Assistant Examiner* — Marissa J Cash*(74) Attorney, Agent, or Firm* — Jacobsen IP Law(57) **CLAIM**

The ornamental design for an unmanned aerial vehicle, as shown and described.

DESCRIPTION

FIG. 1 is a top, left, front perspective view of an unmanned aerial vehicle showing our new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken line showing of portions of the unmanned aerial vehicle depicts environment and forms no part of the claim.
